ROTARY TABLE

Application filed March 26, 1928. Serial No. 264,690.

This invention is a spider for holding a string of well piping as it is withdrawn or inserted in a well, the present invention being an improvement upon our copending application Ser. No. 264,691, filed March 26, 1928, and relating particularly to a spider construction built into a usual rotary table and adapted to support a string of rotary drill pipe as it is withdrawn or lowered 10 through the rotary table, or adapted to be shifted to inoperative position in the rotary table where it will not hinder usual working of the rotary drilling apparatus.

The spider construction preferably provides at least a three point gripping engagement, with the gripping jaws defining a closed annulus surrounding the drill pipe and adapted for dependent, counterbalanced shifting to either operative or inoperative 20 position so as to provide for operation with minimum effort and insure a positive and uniform gripping action which will accurately center the drill pipe in the gripping annulus and avoid all distortion of the pipe.

It is an object of the invention to so mount the jaw operating means in a rotary table as to provide for rotary driving connections between the respective operating means in order that they may be dependent- 25 ly actuated, without obstructing the bore of the rotary table nor hindering its normal operations when the spider is not in use.

It is a further object of the invention to mount the jaw operating means in suitable 30 recesses in the rotary table, so disposed that the operating connections are free to swing the jaws to operative and inoperative position, and are adapted for reception entirely within said recesses and out of the way 35 when the spider is not in use.

Further objects of the invention will be readily understood from the following description of the accompanying drawings, in 40 which:

Fig. 1 is a plan view of the invention, with the jaws in operative position.

Fig. 2 is a vertical section on the line 45 2-2 of Fig. 1.

Fig. 3 is a fragmentary vertical section

showing the jaws removed and their operating connections in inoperative position.

Figs. 4, 5, 6 and 7 are detail sections on the lines 4-4, 5-5, 6-6, and 7-7 of Fig. 1.

The spider is adapted to be built into a usual rotary table 1 having the bore 2 countersunk at its upper end as shown at 3 to receive the usual master bushing which is employed when a string of drill pipe is gripped in the bore of the table and rotated thereby.

The gripping jaws of the spider are detached from their operating connections when the rotary table is in use for the drilling operation, and the jaw operating means are swung back out of the way in suitable recesses communicating with bore 2 so as to allow the master bushing being placed in the bore for proceeding with the drilling. When the spider is to be used the master bushing is removed and the jaw operating means may then be swung from their recesses and the jaws mounted thereon, so that dependent movement of the operating connections will swing the jaws to either operative or inoperative position.

In order to provide at least a three point gripping engagement by the jaws and still accommodate the spider mechanism in the rotary table so as not to interfere with normal drilling operations, it is preferable that four gripping jaws and their corresponding operating connections be employed, and such is the construction herein shown and described.

As an instance of this arrangement 55 elongated recesses 5 are provided in the upper surface of table 1 and communicate with the counter-bore 3, and are four in number equi-distantly circumferentially spaced with the ends of adjacent recesses connected by 60 elongated recesses 6 which are also perpendicular to radii of bore 2 but need not necessarily open into the counter-bore 3. The operating means for the gripping jaws are mounted in the respective recesses 5, and driving connections between adjacent operating means extend along the respective recesses 6.

The jaw operating means comprise shafts 10 journaled in axially spaced bearing lugs 100

11 in recesses 5, and a pair of arms 12 is fixed on each shaft between its bearing lugs, and at their free ends the pairs of arms carry jaws 13 which cooperate when swung to operative position to define a closed annular gripping means concentric with bore 2 and adapted to engage the string of drill pipe extending therethrough. When moved to inoperative position the gripping jaws disengage the string of drill pipe and are swung back to substantially horizontal position overlying the recesses 5 so that the string of drill pipe may be raised or lowered without obstruction by the jaws.

15 The jaw which is carried by each pair of arms 12 is readily detachable therefrom, and is shown as an elongated acute structure preferably having its concave gripping surface transversely serrated, and provided at 20 its convex surface with a lug 18 adapted for reception between the pair of arms 12 and connected thereto by a removable pin 20 so that concave bearing lugs 19 which project from the convex surface of 25 the jaw are journaled on bearing surfaces 17 at the swinging extremities 16 of arms 12.

In order that the cooperating jaws may define a closed annulus when in operative position, they each embrace an arc of substantially 90° when four of such jaws are employed as in the embodiment illustrated, and by the mounting for the jaws as has been described it will be seen that by dependently rotating shafts 10 the jaws are 35 adapted for dependent movement to operative or inoperative position as shown in full and dotted lines in Fig. 2.

The shafts 10 are adapted for dependent rotation by driving connections extending 40 along recesses 6, and these driving connections are shown as counter-shafts 25 journaled in bearing lugs 26 in recesses 6, with the adjacent ends of shafts 10 and 25 provided with meshing bevel gears 27 whereby 45 turning any one of the shafts 25 will dependently swing all of the gripping jaws to operative or inoperative position. The shafts 25 may be provided with collars 28 which have bores 29 adapted for 50 reception of a suitable operating lever (not shown), so that with such a lever engaged in any one of said bores the lever may be manually shifted to swing all of the jaws to operative or inoperative position.

55 Segments of gears 27 are preferably cut away as shown at 31, and the gears as well as collars 15, through which the arms 12 are secured to shafts 10, are preferably counterweighted as shown at 32, 33 respectively, 60 in order to form a counterbalanced construction whereby the jaws may be readily swung to either operative or inoperative position with the counterweights aiding such swinging movement from the moment that it is 65 initiated; and the recesses 5 and 6 are of

suitable size to permit free swinging movement of the counterbalanced operating arms and rotation of the bevel gears, with the entire operating connections preferably remaining substantially entirely below the surface of the rotary table. The rear walls of recesses 5 are preferably cut away adjacent the surface of the rotary table so as to form inclined abutment surfaces 40 for limiting swinging of arms 12 to their inoperative position, the said inclined abutment surfaces being so positioned as to allow the jaws to swing rearwardly substantially entirely beyond the vertical dead centers of the operating arms as shown in dotted lines in Fig. 2.

When drilling is to be resumed after using the spider, the jaws 13 are removed by withdrawing pins 20, and arms 12 are swung downwardly into prolongations of recesses 5 which extend into the wall of bore 2 as shown at 35, the parts being so arranged that with the arms thus inoperatively positioned they no longer project into either bore 2 or counter-bore 3 and the master bushing A may consequently be replaced in the bore of the rotary table for resuming the drilling operation. The entire spider structure is thus adapted for reception within the rotary table where it is out of the way, but it is immediately available for use by removing the master bushing of the rotary table and mounting the jaws on the ends of their arms.

We have thus provided an extremely 100 practical spider structure embodying at least a three point gripping engagement, and adapted for mounting in a usual rotary table so as to in no way interfere with normal operation of the rotary table during 105 the drilling operation, but being immediately available when it is desired to use the spider, with the gripping elements dependently operated so that the pressure is uniform throughout the gripping annulus.

We claim:

1. In combination, a base provided with a bore adapted to receive a string of well piping and also provided with a recess communicating with said bore, an arm having a pivotal mounting in said recess, and a gripping jaw connected to the swinging end of the arm and adapted to engage the well piping or be swung back to inoperative position above the base by swinging movement of the arm, the said recess having a rear abutment surface so positioned as to permit rearward swinging of the arm to a position whereby substantially the entire gripping jaw is swung rearwardly beyond the vertical dead center of said pivotal mounting for the arm.

2. In combination, a base provided with a bore adapted to receive a string of well piping and also provided with a recess com-

municating with said bore, an arm having a pivotal mounting in said recess, and a gripping jaw detachably connected to the swinging end of the arm and adapted to engage the well piping or be swung back to inoperative position above the base by swinging movement of the arm, the swinging end of the arm being adapted for reception in the recess clear of the bore after the jaw is detached from the arm.

10 3. In combination, a base provided with a bore adapted to receive a string of well piping and also provided with a recess communicating with said bore, an arm having a pivotal mounting in said recess, and a gripping jaw detachably connected to the swinging end of the arm and adapted to engage the well piping or be swung back to inoperative position above the base by swinging movement of the arm, the swinging end of the arm being adapted for reception in the recess clear of the bore after the jaw is detached from the arm, with said recess extending into the base to a depth whereby substantially the entire arm is below the upper surface of the base when the arm after the jaw is detached therefrom is received in the recess clear of the bore.

15 4. In combination, a base provided with a bore adapted to receive a string of well piping and also provided with a recess communicating with said bore, an arm having a pivotal mounting in said recess, and a gripping jaw detachably connected to the swinging end of the arm and adapted to engage the well piping or be swung back to inoperative position above the base by swinging movement of the arm, the said recess having a rear abutment surface so positioned as to permit rearward swinging of the arm to a position whereby substantially the entire gripping jaw is swung rearwardly beyond the vertical dead center of said pivotal mounting for the arm, and the swinging end of the arm being adapted for reception in the recess clear of the bore after the jaw is detached from the arm.

20 5. In combination, a base provided with a bore adapted to receive a string of well piping and also provided with a recess communicating with said bore, an arm having a pivotal mounting in said recess, and a gripping jaw detachably connected to the swinging end of the arm and adapted to engage the well piping or be swung back to inoperative position above the base by swinging movement of the arm, the said recess having a rear abutment surface so positioned as to permit rearward swinging of the arm to a position whereby substantially the entire gripping jaw is swung rearwardly beyond the vertical dead center of said pivotal mounting for the arm, and the swinging end of the arm being adapted for reception in the recess clear of the bore after the jaw is

detached from the arm, with said recess extending into the base to a depth whereby substantially the entire arm is below the upper surface of the base when the arm after the jaw is detached therefrom is received in the recess clear of the bore.

25 In testimony whereof they have affixed their signatures to this specification.

HERBERT W. GOETZ.
